UNITED STATES PATENT OFFICE.

VALERIUS D. ANDERSON, OF CLEVELAND, OHIO.

PRESS.

SPECIFICATION forming part of Letters Patent No. 602,929, dated April 26, 1898.

Application filed August 13, 1896. Serial No. 602,634. (No model.)

To all whom it may concern:

Be it known that I, VALERIUS D. ANDERSON, a citizen of the United States, residing at Cleveland, in the county of Cuyahoga and 5 State of Ohio, have invented certain new and useful Improvements in Presses, of which the following is a specification.

My present invention pertains to presses for extracting oil, grease, moisture, juices, 10 &c.; and it consists, primarily, in the combination of two endless flexible belts, one or both in the form of a chain or jointed metal band.

The invention further consists in means for feeding the press, maintaining the belts in 15 proper working position and relation, and insuring the requisite pressure, and in other features, details, and combinations hereinafter set forth.

In the accompanying drawings, Figure 1 is 20 a side elevation of the press in its preferred form; Fig. 2, a vertical cross-section through the pressing-belts and a part of the frame; Figs. 3 and 4, detail views of the bridge-pieces which support the lower belt between the pres- 25 sure-rolls, and Figs. 5 and 6 side elevations of modified forms of the press.

In the treatment of garbage, brewers' and distillers' grains, and other substances containing a large percentage of water, with or 30 without oil or grease, much difficulty has been experienced in removing a fair or adequate percentage of such fluid or semifluid matters.

I have ascertained by extended and costly investigation and experiment that in order to 35 express any large percentage of the fluid or semifluid contents of a charge it is essential that it be subjected to a series of compressions, each heavier or stronger than that preceding, and it is important to permit the pres- 40 sure to lessen between succeeding compressions. This relief from pressure permits the mass to open and allows the fluid to escape from its interior. The vital point, however, is that the pressure be exerted along a nar- 45 row line and thus concentrated on a compa- ratively small surface at any given instant. With sufficiently heavy pressure and by following out this mode of pressing I am enabled to extract a percentage of moisture, oil, grease, 50 &c., far in excess of anything hitherto accomplished so far as I have been able to learn through many years of active work in this line.

In another application, Serial No. 599,538, filed in my name on the 17th day of July, 1896, I have set forth this plan of pressing by 55 the aid of an endless chain belt acting in conjunction with the interior surface of a hollow drum or barrel. The present constructions embody this principle, but are better suited to certain classes of work or for use in certain 60 situations and admit of more ready feeding and delivery of material.

Referring first to Fig. 1, A indicates a strong frame, which may be of metal or of wood, or of the two combined, and of such dimensions 65 as the purposes of the press render expedient. Journalized in suitable boxes or bearings *a* upon this frame are the shafts or axles *b* of two broad-faced wheels or drums *B*, about which is carried an endless belt *C*, composed 70 of broad flat lags *c*, jointed one to another after the manner of a link belt or in any usual or convenient fashion. The joint-pins *d*, by which the lags *c* are connected, are extended outward beyond the sides of the lags to form 75 axles or spindles for rollers *D*. (Shown in Figs. 1 and 2.)

E indicates a track or bearing rail or bar, of which there are two, one bolted to either side of frame *A* directly over the lines of 80 travel of rollers *D*, for which rollers they form tracks or backings, thus serving to prevent the rollers, and consequently the lags *c*, from being lifted up above a predetermined plane while passing from the lower side of one wheel 85 or drum *B* to that of the other.

F *F* indicate a second pair of wheels or drums, the axles *e* of which are journaled in frame *A* at a lower level than axles *b* of wheels *B*, and also at a greater distance apart 90 or nearer the ends of the frame. These wheels or drums serve to support and carry a second chain belt *G*, which is advisably composed of a plurality of separate chains *f*, capable of yielding independently and serving also to 95 permit the escape of moisture or liquid between them. Hitherto it has been customary to make such chains of links or lags the full width of the belt, and as a consequence it has been found difficult to effect or secure the 100 prompt and complete escape of moisture or liquid from the mass lying between the pressing-surfaces. It is also found that by making the belt of separate chains lying closely

together it will adapt itself to the irregularities of the material or the mass entering between the chains and will permit a better distribution and rearrangement of particles 5 between the pressing-surfaces. Incidentally this construction permits the ready widening or narrowing of the pressing-surfaces.

The several chains *f* are composed of flat lags or links, pin-jointed to one another, and 10 one at least is provided with teeth or projections *g* to enter cavities in the wheels *F* to insure movement with the wheels. This is found quite important for the reason that in 15 working upon substances containing grease or oil the belt is liable to slip, and thus to cause flattening of the wheels and unsatisfactory work, if indeed any work be possible.

H indicates a pressure-roller, of which three are represented in the drawings, each journaled in a sleeve *h*, pivotally supported in a bail or yoke at the lower end of a tension-rod *I*, passing through a bracket *J* at the top of frame *A* and encircled by a powerful spring *K*, the compression of which is effected and 25 determined by a nut *L*, acting upon an interposed disk *M*. The springs *K* tend to lift the rollers *H* and to cause them to bear with great force beneath the upper stretch of chain belt *G*, thus in turn causing the belt *G* to bear 30 against the lower face of belt *C* or against any material between the opposing faces of the two belts. It is to enable it to withstand 35 this pressure that belt *C* is furnished with rollers *D* and these arranged to traverse the backing rails or bars *E*, as above noted.

To limit and determine the approximation of the opposing surfaces of belts *C* and *G*, the rods *I* are screw-threaded to a point somewhat below the brackets *J*, and nuts *N* are screwed 40 thereon beneath the brackets or before the rods are passed through them. These nuts can be set up or down at will and form stops to limit the rise of the rods and consequently that of the rollers *H*. Hence however great 45 the compression of the springs may be the approach of the belt-faces will be limited by the nuts *N*.

To prevent the rollers *H* from shifting laterally, the sleeves *h* are guided in slots or openings in a raised plate *O*, bolted or otherwise made fast to the frame *A*.

It will be seen that if no provision be made to the contrary the belt *G* or its parts would sag between the rollers *H*. To preclude this, 55 I provide saddles *P* of the form shown in Figs. 3 and 4. These comprise a body portion or bar *i*, having concave under faces to conform closely to the contour of the rollers *H*, and end plates *j*, extending from one roller- 60 axle to the other and provided with seats *k* to fit said axles. By this construction the saddles are retained in place, as indicated in Fig. 3.

The rollers *H* are provided with cavities or 65 recesses *l* to receive the teeth or studs *g* of the chain-lags, so that the rolls are caused to rotate with the same surface speed as that of

the proximate face of belt *G*, and the saddles *P* are formed with grooves *m* to permit the passage of said teeth.

Motion is imparted to the wheels and belts from a power-shaft *Q* through a pinion *R* and gear-wheels *S* and *T*, carried by the shafts or axles of wheels *B* and *F*, respectively, as shown in Fig. 1.

U indicates a feed-hopper supported by frame *A* and arranged with its delivery end or outlet at the bite of the two belts *C* and *G*, the lower belt extending outward beneath the hopper, as shown, and thus insuring the proper retention of the material.

At the sides of the belts *C* and *G* and overlapping the space or line between them are guard plates or bars *V*, which serve to keep the belts in proper position, and also to prevent escape of material at the sides of the belts. These guards are shown in Figs. 1 and 2. The material after passing between the belts, subject to the increasing pressure of successive rollers *H*, is discharged over the 85 rear wheel *F* upon the ground or into any suitable receptacle.

In Fig. 5 I have shown a press embodying the same general principles of construction, but have represented the frame as of substantially semicircular form, with the pressure-rollers above and the springs below, the belt-rollers bearing upon a track or flange formed upon the frame.

Fig. 6 shows still another modification, in 100 which a belt *A'* of any suitable character, but preferably of woven or fibrous material, is carried about two wheels or drums *B' B'*, and a chain belt *C'*, provided with supporting-rollers *D'*, passes over a curved track or rail *F'* and has its inner stretch or part pressed 105 against the belt *A'* and presses this against wheel *B'*, through the action of presser-rolls *G'*, provided with springs *H'* and temper-screws *I'*.

The construction illustrated in Fig. 1 is preferred and after that the construction shown in Fig. 5.

Having thus described my invention, I claim—

1. In a press, the combination of a frame; wheels or drums mounted in said frame; an endless chain belt passing about said wheels or drums; supporting bars or rails within said belt to guide and support its working face; a second pair of wheels or drums; a second endless chain passing about said wheels or drums, composed of separate parallel chains, and having its face opposed to that of the first belt; and means substantially such as shown and described for pressing and holding the second belt against or close to the first, throughout an extended area.

2. In a press, the combination of a frame *A*, wheels or drums *B B* mounted therein; a chain belt *C* passing about said wheels; rollers *D* carried by said chain belt; tracks or bars *E* for said rollers; wheels or drums *F*, *F*, mounted in the frame *A*; endless chain

belt G passing about said wheels and consisting of a series of separate parallel chains; and means substantially such as described and shown for pressing and holding belt G against 5 or close to belt C, throughout an extended area.

3. The herein-described press, comprising a frame A; wheels or drums B B; endless chain belt C provided with rollers D; track- 10 rails E E for said rollers; wheels or drums F F; endless chain belt G; pressure-rollers H serving to press belt G toward belt C; saddle P located between the rollers H; draw- rods I; springs K; and means for determin- 15 ing the compression of said springs.

4. In combination with frame A having guide-plates O; wheels B B mounted in said frame; endless chain belt C passing about said wheels; supporting-bars E for said belt; 20 wheels F F also mounted in frame A; endless chain belt G passing about said wheels; pressure-rollers H beneath the upper section of belt G; collars or boxes h applied to the journals of rollers H and guided by plate O; draw- rods I carrying the sleeves h, and springs K 25 applied to said rods.

5. In combination with frame A; endless chain belts C and G and their supporting or carrying wheels; guide-plates O; sleeves or

collars h adapted to support a series of rollers guided by said plates; draw-rods I carrying said sleeves; and springs K applied to said rods.

6. In combination with chain belt C and its supports; chain belt G, consisting of a plurality of parallel chains, one provided with teeth g; carrying wheels F F for said chain; pressure-rollers H for chain G; and a saddle P interposed between proximate rollers H to prevent sagging of belt F, the wheels F, rollers H and saddle P being all recessed to receive or permit the passage of teeth g; substantially as described and shown.

7. In a press, the combination of two endless belts arranged face to face through a portion of their length, one composed of separate parallel chains; carrying wheels or drums for said belts; and means substantially such as shown and described for pressing and holding the opposing faces of the two belts in close proximity.

In witness whereof I hereunto set my hand in the presence of two witnesses.

VALERIUS D. ANDERSON.
